UNITED STATES PATENT OFFICE.

JOSEPH P. MORNEAU, OF APPLETON, WISCONSIN.

STERILIZING-CASE FOR POCKET-THERMOMETERS.

1,247,440.

Specification of Letters Patent. Patented Nov. 20, 1917.

Application filed April 21, 1914. Serial No. 833,470.

To all whom it may concern:

Be it known that I, JOSEPH P. MORNEAU, a citizen of the United States, residing at Appleton, in the county of Outagamie and State of Wisconsin, have invented certain new and useful Improvements in Sterilizing-Cases for Pocket-Thermometers, of which the following is a specification.

My invention relates to improvements in sterilizing cases for pocket thermometers.

The present invention aims to improve, simplify and render more efficient the article disclosed in my pending application for Letters Patent, Serial Number 757,171, filed March 27, 1913, for an improved sterilizing case for pocket thermometers.

A main object of the invention is to provide a means whereby the tube containing the sterilizing liquid may be fastened to the annulus employed in such manner that alcohol, which is preferably employed as the sterilizing medium, cannot effect the fastening by loosening the tube.

A second object of the invention is to provide a sterilizing liquid and thermometer-retaining tube construction simpler than that employed in the device of said application, and being in the nature of a tube of substantially the same diameter throughout, but which may have interior projections to act as stops and rests for the thermometer basket employed, and in either construction of tube, with the basket so constructed as to engage the interior wall of the tube frictionally so that the basket may be adjusted longitudinally of the tube and remain in adjusted position to accommodate thermometers of different lengths.

A third object is to provide a construction wherein the cap and annulus employed will not adhere or "stick" to each other to such an extent as to render it difficult to remove the cap from the annulus and to this end to so form the parts that the lower edge of the cap will not be in contiguous relation with the adjacent shoulder of the annulus.

A fourth definite object is to provide an effective construction carrying out the said first object wherein the tube containing the sterilizing liquid may be fastened to the annulus solely by means of a rubber tube, and

A fifth definite object is to provide a detachable chain-attaching ring coöperating with the detachable annulus and a sheath 55 employed so as to be fastened in place when the annulus and sheath are fastened together.

The present preferred embodiment of the invention possessing the advantages and attaining the objects set forth, is hereinafter 60 particularly described and is illustrated in accompanying drawings:—

In said drawings:

Figure 1 is a vertical sectional view illustrating the improved article, this construction employing a sheath and a chain-attaching ring.

Fig. 2 is an elevation of the improved device with the sheath and chain-attaching ring omitted.

Fig. 3 is a vertical sectional view through a modified form which may also employ the sheath and ring as shown.

Fig. 4 is an enlarged cross sectional view taken through the tube illustrated in Fig. 3 75 at the basket-supporting projections thereof, and

Fig. 5 is a fragmentary vertical sectional view through a modified form.

Referring specifically to the drawings and 80 wherein like reference characters designate like or corresponding parts, and first to Figs. 1 and 2, 1 designates a tube which is closed at the bottom and open at the top and of the same diameter throughout, the tube being 85 made of glass or other transparent material. This tube 1 is fastened to an annulus 2 which has a central bore 3 arranged in elongation of the bore of the tube so that a thermometer 4 may pass through the annulus and into 90 the tube. The bore 3 at the lower portion of the annulus is enlarged as shown and a shoulder or stop wall 5 is consequently provided. The tube 1 extends into the enlarged portion of bore 3 and abuts against the 95 shoulder or wall 5. Intermediate the annular wall of the enlarged portion of the bore and the outer wall of the tube 1 at its top, is a flexible or rubber fastening tube 6. This fastening tube 6 effectively grips the 100 walls mentioned and maintains the tube 1 effectively fastened to the annulus and due to the fact that the upper edge of the tube 1 abuts against the wall 5, the annulus can-

not be moved onto a tube 1 more than the desired extent.

In my pending application Serial Number 757,191, above referred to, the device shown uses cement for fastening the tube for the sterilizing liquid to the annulus. Alcohol is the preferred sterilizing medium and alcohol as is well known acts on the cement in such a way as to loosen the tube. This is a great objection to be overcome and this objection is overcome by employing the fastening means consisting of the rubber tube at 6.

Annulus 2 is reduced at a portion 7 thereof providing a shoulder at 8. Further the annulus 2 has a reduced exteriorly screw threaded nipple 9 below the reduced portion 7. The screw threads of the nipple 9 are engaged by screw threads 10 of a protecting sheath 11. Prior to attachment of the sheath, a ring 12 may be placed over the reduced portion 7. This ring 12 may have fastened thereto a link at 13, or any other suitable means to which a chain or flexible attaching element may be secured. When the ring 12 is fastened in place, it will be noted that it is prevented from longitudinal movement with respect to the annulus, by means of its engagement with the shoulder at 8 and engagement with the upper end of the sheath.

Annulus 2 is further provided with a second reduced exteriorly screw threaded nipple as is shown at 13. A cap 14 having a bore 15 is enlarged at its lower end and provided with screw threads at 16 to detachably engage the screw threads of nipple 13. Intermediate the upper end of the nipple 13 and the horizontal wall of the enlargement of the cap 14, which wall may be designated 17, is mounted a gasket 18 of rubber or other suitable material. It will be noted that when the cap 14 is fastened in place as seen in Fig. 1, the overall length of the nipple 13 and gasket 18 is greater than the length of the screw threaded wall of the cap. Thus when the cap is fastened, the same will not abut at its lower end with the adjacent wall of the annulus which may be for convenience designated 19. This is a very important feature inasmuch as I have found in actual practice that with a construction wherein the lower wall of the cap and a wall of the annulus abut, that the parts adhere or "stick" and it is sometimes quite difficult to unscrew the cap. By so forming the parts that such walls never contact or abut, this objection is obviated.

Thermometer 4 is merely a conventional form but no matter what form is carried by the article, it is supported so that the same extends through the bore 8, bore of the gasket 18 and bore 15 of the cap, in addition to extending into the tube 1. As the means for supporting the thermometer within the tube 1, I employ a basket 19

made of a spirally wound wire, for instance a wire of silver, several convolutions of which basket are so tensioned as to tend to expand and effectively frictionally engage the interior wall of the tube 1 so as to thereby position the basket. This construction enables me to employ a tube which may be of the same diameter throughout and thereby very cheap to manufacture, and a construction wherein the basket or thermometer supporting means may be adjusted longitudinally of the tube in order to accommodate thermometers of different lengths. The convolutions of the basket 19 do not touch and hence the basket does not prevent the free flow of liquid within the tube. Should it be necessary to vary the position of basket 19 in order to accommodate the thermometers of different lengths, the basket may be engaged by a suitable hook or other instrument and move longitudinally of the tube 1. The basket should support the thermometer so that the upper end thereof projects beyond the basket 18 to facilitate grippage by the fingers prior to removal.

Tube 1 is adapted to contain a suitable quantity of sterilizing liquid, for instance alcohol, and the portion of the tube beyond the basket 19 serves as a reservoir for the liquid which should thoroughly immerse the thermometer upon sterilization. The sterilization is effected by inversion of the tube 1 one or more times. An air tight joint of the cap with the annulus is provided and is desirable so that leakage will not occur and volatilization of the alcohol will not take place. The tube 1 may be of any desired length and is preferably of such length that it will contain a quantity of the sterilizing liquid sufficient to last several days.

Sheath 11 may be transparent or opaque as desired and made of any suitable material. Suitable windows or sight openings may be provided in the sheath at 20 in order that the depth of submergence of the thermometer may be observed and also in order that the quantity of liquid within the tube may be observed.

As the sheath 11 is merely for the purpose of protecting the tube 1, the sheath may be dispensed with in which event the article would appear as seen in Fig. 2. As the parts of Fig. 2 are similar to the parts of Fig. 1, the numerals used in connection with Fig. 1 are also used in connection with Fig. 2.

In Figs. 3 and 4 a modified form is shown. Except with respect to the sterilizing liquid containing tube, which in this figure is designated 21, the other parts are exactly similar to those of Fig. 1 and therefore the same reference numerals have been applied thereto. This liquid containing tube 21 is provided with one or more indentations in order to form projections or rests 22 in- 130

teriorly of the tube in order that the basket 19 may rest thereon, at one of its convolutions, and mount the basket in one position against movement to an improper depth 5 into the sterilizing liquid.

5 A further modification is shown in Fig. 5. This figure merely illustrates the transfer of the nipple 13 of the annulus as seen in Fig. 1, to the cap. In this figure the cap 0 is designated 22, the nipple which is the equivalent of nipple 13 is designated 23 and the annulus is designated 24.

Various modifications in the details of construction may be resorted to without departing from the spirit and scope of the invention.

Having thus described my said invention, what I claim and desire to secure by Letters Patent is:—

- 0 1. A sterilizing case having a tube to contain a sterilizing medium, and an article supporting device within the tube expansible at its outer edge to frictionally engage the inner wall of the tube, said device being adjustable longitudinally of the tube to enable the tube to accommodate articles of different lengths and the frictional engagement of the supporting device serving to maintain the device in adjusted positions.
- 5 2. A sterilizing case having a tube to contain a sterilizing medium, an article supporting device within the tube expansible at its outer edge to frictionally engage the inner wall of the tube, said device being adjustable longitudinally of the tube to enable the tube to accommodate articles of different lengths, the frictional engagement of the supporting device and tube serving to maintain the supporting device in adjusted positions, and means extending interiorly of the tube intermediate its ends to limit the movement of the device in one direction.

3. A sterilizing case having a tube to contain a sterilizing medium, an article supporting device frictionally supported within the tube, said device being adjustable longitudinally of the tube to enable the tube to accommodate articles of different lengths, and said tube being indented to provide a projection extending interiorly of the tube to limit the depth of movement of the device within the tube.

4. A sterilizing case having a tube to contain a sterilizing medium, and an article supporting device within the tube frictionally engaging the inner face of the tubular wall of the tube consisting of a helical wire with the convolutions non-contiguous, said device being adjustable longitudinally of the tube to enable the tube to accommodate articles of different lengths, the frictional engagement between the supporting device and the inner wall of the tube serving to maintain the article supporting device in different positions.

5. A sterilizing case having a tube to contain a sterilizing medium, an article supporting device within the tube frictionally engaging the inner wall of the tube consisting of an expansible spiral wire having its 70 convolutions non-contiguous, and said tube being provided with an interior projection integral with same to limit the depth of movement of the device within the tube, said device being adjustable longitudinally of 75 the tube to enable the tube to accommodate articles of different lengths.

6. A thermometer case comprising a receptacle of a length greater than the thermometer to be incased to provide a space 80 beyond the extent of said thermometer and in the lower end of said receptacle as a liquid chamber, said receptacle having a constriction at the proximate point of greater downward extent of the thermometer therein 85 and a basket received within said receptacle and held by said constricted portion to receive the lower end of said thermometer and support the same against side and downward movement.

90 7. A thermometer case comprising a receptacle in the form of a single closed ended tube of a greater length than the extreme extent of the thermometer and provided with an inwardly extending shoulder at the proximate point of the inward extent of the thermometer therein, and an open-work spirally wrapped wire basket frictionally held within said receptacle against the shoulder to receive the lower end of the thermometer and hold said thermometer against downward and side movement and yet permit the free passage of liquid to all parts of the receptacle.

105 8. A thermometer case comprising a receptacle in the form of a single closed ended tube of a greater length than the extreme extent of the thermometer and provided with an inwardly extending shoulder at the proximate point of the inward extent of the thermometer, an open work spirally wrapped wire basket frictionally held within said receptacle against the shoulder to receive the lower end of the thermometer and hold said thermometer against downward and side 110 movement and yet permit the free passage of liquid to all parts of the receptacle, and a protective covering secured around said receptacle, and provided with longitudinally extending slots forming windows to permit 115 observation of the liquid chamber and the thermometer chamber provided within the receptacle.

120 9. A thermometer case comprising a receptacle of a length greater than the thermometer to be incased and constricted to have an inner projecting shoulder at a point proximate the inner extent of the thermometer to thus form a thermometer chamber and a liquid chamber, and a spirally 125 180

wrapped inverted cone-shaped basket received within the thermometer chamber to bear against said shoulder with the apex of said basket disposed in a relation to receive the lower end of the thermometer and support the same against downward and side movement.

Copies of this patent may be obtained, for five cents each, by addressing the "Commissioner of Patents, Washington, D. C."

In testimony whereof I affix my signature in presence of two witnesses,

JOSEPH P. MORNEAU.
